UNITED STATES PATENT OFFICE.

THOMAS S. HOMANS, OF HEMPSTEAD, NEW YORK, ASSIGNOR TO INTERNATIONAL TYPE-SETTING MACHINE COMPANY, OF NEW YORK, N. Y., A CORPORATION OF NEW YORK.

LINOTYPE-MACHINE.

1,127,625.

Specification of Letters Patent.

Patented Feb. 9, 1915.

Application filed August 16, 1912. Serial No. 715,464.

To all whom it may concern:

Be it known that I, THOMAS S. HOMANS, a citizen of the United States, residing at Hempstead, in the county of Nassau and State of New York, have invented new and useful Improvements in Linotype-Machines, of which the following is a specification:

The present invention relates to improvements in linotype machines and more particularly to the trimming mechanism for shaving the sides of the slugs after they are ejected from the mold.

Heretofore it has been customary to employ a mold, one side of which is fixed or constant, the respective knife for trimming the corresponding side of the slug being also fixed or constant, the other side of the mold and the respective knife being adjustable in order to adapt these elements to the production of slugs of different sizes. Modern requirements of machine composition, however, demand much larger slugs than formerly and it is difficult to obtain the proper adjustment of the mold for the production of such slugs, when, as heretofore, but one side of the mold is adjustable. It is therefore desirable to adjust both sides of the mold, that is to say, to shift the entire mold in order to adapt it to the production of the larger sized slugs, and with such a mold, it becomes desirable to use a trimming mechanism wherein both knives are adjustable to conform to the different settings of adjustments of the mold, that is to say, the entire trimming mechanism is adjustable.

It is the primary object of the present invention to provide a trimming mechanism of this character.

To these and other ends, the invention consists in certain improvements, and combinations and arrangements of parts, all as will be hereinafter more fully described, the novel features being pointed out particularly in the claims at the ends of the specification.

In the accompanying drawings:—Figure 1 represents a front elevation of a portion of a linotype machine showing the same equipped with the preferred embodiment of the present invention; Fig. 2 represents a rear elevation of the same portion of the machine with the parts removed and show-

ing the improved trimming mechanism; Fig. 3 represents a horizontal section on the line 55—55 of Fig. 2, the section, however, including a portion of the mold wheel and the mold thereon; Fig. 4 represents a section on the line 4—4 of Fig. 2; Fig. 5 represents a section on the line 5—5 of Fig. 2; Fig. 6 is a perspective view of the slide for the trimming mechanism.

Similar parts are designated by the same reference characters in the several views.

The preferred embodiment of the invention is shown in the accompanying drawing and will be hereinafter described in detail, but it will be understood that the invention is not limited necessarily to the particular construction shown, as equivalents may be used within the scope of the claims. The invention is applicable particularly to the well-known linotype machines and is in the present instance shown applied to a machine of that type.

In the present instance, 1 designates the mold wheel which may be of the usual construction and may be operated by the usual pinion 2 carried by the operating shaft 3. The mold which is carried by the mold wheel 10 embodies the members 4 and 5, the member 4 corresponding to the usual mold body and the member 5 corresponding to the usual mold cap. Heretofore, it has been customary in practice to secure the mold body 15 in a fixed or constant position on the mold wheel and to adjust the mold for the production of slugs of different sizes by interposing liners of different thicknesses between the mold body and the mold cap. For the purposes of the present invention, however, both members of the mold are adjustable relatively to the mold wheel as well as with respect to one another, and while different mountings may be used to provide 20 for these adjustments of the mold, a mounting such for example as that shown in my prior application, No. 704,853 filed June 20, 1912 may be used, it being sufficient to note that in the present instance, the mold members 4 and 5 are adjustable relatively to one another as well as to the mold wheel, and in the preferred construction, the matrix-positioning ledge 6 is fixed to or occupies a constant position on the mold wheel. The elevator 7 serves as usual to present a line of

matrices to the mold, and the vise jaws 8 serve in the usual way to clamp the line of matrices and to hold the matrices in correct position during the casting operation.

5 After the slug has been cast, the mold wheel is rotated in the usual way to a position where the ejector removes the cast slug from the mold, and during the removal or ejection of the slug from the mold, the sides thereof are 10 shaved by trimming knives. In the present instance, 9 and 10 designate the trimming knives and these knives are positioned to receive the slug between them when the slug is ejected from the mold. Heretofore, it 15 has been the practice to employ a trimming mechanism wherein one knife was fixed or occupied a constant position and the other knife was adjustable. According to the present invention, however, both of the trimming knives are adjustable whereby they 20 may be set to conform to the different settings of the adjustable mold members 4 and 5. In the construction shown in the present instance, the trimming knives 9 and 10 are 25 both mounted on a slide or shiftable carrier 11, this slide being mounted preferably on the vise frame 12 and is held and guided thereon, by gibbs 13, 14 and 15. Means is provided for adjusting the slide according 30 to the different settings of the trimming knives, an adjusting screw 16 being shown in the present instance which is journaled in a bearing 17 formed on the slide and has threads which coöperate with an abutment 35 18 of the vise frame. A milled head or wheel 19 is provided on the screw for operating it and a pointer 20 may be provided to coöperate with a graduated scale 21 on the milled head or wheel. Means is also 40 provided for locking or retaining the slide in different adjusted positions, one of the gibbs (the gib 15 in the present instance) being provided with a clamp 22 embodying a screw 23 and a nut 24, the latter having 45 an operating handle 25 which may be manipulated readily to clamp and release the slide. The knife 9 in the construction shown is attached to this slide 11 and it may be fixed on the slide while the knife 50 10 is supported or carried by the slide and is provided with means for adjusting its relation to the slide. Such adjusting means may be of different kinds, that shown in the present instance being fully disclosed and 55 claimed in the pending application of William E. Bertram, Serial No. 661,936 filed November 23, 1911, it embodying, briefly, a knife-block 26 which is secured to the lugs 27 on the slide, a member 28 which is 60 shiftable on the knife-block by the handle 29, the knife 10 being secured to and carried by the shiftable member 28, and a pin 30 is provided which is adapted to coöperate with the graduated device 31 to position the knife for the different sized slugs.

In operating a machine embodying the present invention, the mold body and cap are set apart as usual by interposing liners of appropriate thickness for the production of slugs of the desired size, and the 70 entire mold is shifted with respect to the mold wheel to a predetermined point, the slug-receiving opening between the trimming knives may be set by the handle 29 which adjusts the knife 10, and both trimming knives may be shifted quickly and 75 easily to a position to correspond with that of the mold by manipulation of the wheel 19 which operates to shift the slide 11 carrying both knives.

80 I claim as my invention:—

1. The combination of a mold for casting linotype slugs, trimming mechanism for shaving the sides of the slugs, and means for bodily setting in different predetermined positions the entire trimming mechanism transversely to the mold cavity to conform to varying positions of the mold.

2. The combination of a mold for casting linotype slugs, the mold being adjustable to 90 vary the size and position of the cavity thereof, and trimming mechanism for shaving the sides of the slugs, embodying knives adjustable bodily in a direction transversely of the mold cavity to conform to variations 95 in the position of the mold cavity.

3. The combination of a mold for casting linotype slugs, the mold being adjustable to vary the size and position of the cavity thereof, and trimming mechanism 100 for shaving the sides of the slugs, embodying knives adjustable relatively according to the size of the mold cavity and also adjustable bodily in a direction transversely of the mold cavity to conform to the position 105 of the mold cavity.

4. The combination of a mold for casting linotype slugs, mechanism for trimming the sides of the slugs, embodying a pair of knives, means for adjusting one of said knives relatively to the other according to the size of the slugs, and means for adjusting the knives bodily in a direction transversely of the mold cavity to conform to the position occupied by the mold.

5. The combination of a mold for casting linotype slugs, and mechanism for trimming the sides thereof, embodying an adjustable slide, a pair of knives carried thereby, means for adjusting one of said knives on the slide 110 relatively to the other knife to set the opening between them according to the size of the slug, and means for shifting the slide in a direction transversely of the mold cavity to position the knives according to the position occupied by the mold.

6. In a linotype machine, the combination of a main frame, a mold, a mold-carrying wheel, trimming mechanisms including a 115 knife for trimming the side of the slug

which is cast nearest to the center of the mold wheel, and a slide for supporting said knife, said slide being adjustably mounted on the main frame and extending to the opposite side of the mold wheel to facilitate adjustment.

In testimony whereof I have hereunto set

my hand in presence of two subscribing witnesses.
